Fig. 2.

Des. 182,677

PAGE 3

Fig. 3.

Fig. 4.

Fig. 5.

Figure 1 is a perspective view of a lather making machine embodying my new design viewing the same from the front, top and one side thereof;

Figure 2 is a perspective view, viewing the lather making machine from the rear, top and opposite side thereof;

Figure 3 is a front view of the lather making machine;

Figure 4 is a side view thereof; and

Figure 5 is a top view of the lather making machine.

I claim:

The ornamental design for a lather making machine, as shown.
